UNITED STATES PATENT OFFICE.

LEVIN H. MULLIKIN, OF EASTON, MARYLAND.

BRAKING MECHANISM FOR TALKING-MACHINE MOTORS.

1,395,725.

Specification of Letters Patent.

Patented Nov. 1, 1921.

Application filed March 26, 1920. Serial No. 369,140.

To all whom it may concern:

Be it known that I, LEVIN H. MULLIKIN, a citizen of the United States, residing at Easton, in the county of Talbot and State 5 of Maryland, have invented certain new and useful Improvements in Braking Mechanism for Talking-Machine Motors, of which the following is a specification.

My invention relates to speed regulating 10 mechanism for spring motors such as are used in talking machines.

The object of the invention is to regulate the speed of the motor by means of a non-rotatable element movable back and forth 15 with the speed responsive means and a stop to limit the effective movement of said non-rotatable element to cause the speed-responsive means to exert a pulling action on said non-rotatable element and so effect a braking 20 or retarding action on the motor shaft. In the construction shown, the speed-responsive element is a centrifugal governor and the outward movement of the weights thereof is limited by the predetermined position 25 of the stop and the pull of the governor sleeve upon the non-rotatable member to which it is swiveled or in which it freely turns. The greater the tendency of the 30 weights to fly outwardly due to the speed of the motor, the greater the pull upon the non-rotatable element, and hence a braking or retarding action upon the motor shaft follows. This construction effectively does away with the noise and uneven action generally 35 present where a brake pad is employed in opposition to and to one side of the center of a disk rotating with the governor sleeve.

This object I accomplish by the construction shown on the accompanying drawing, 40 in which—

Figure 1 is a front elevation, and

Fig. 2 is a section on line 2—2, Fig. 1.

The vertical shaft 1, which carries the usual horizontal table, not shown, is provided 45 at its lower end with a worm 2 meshing, as usual, with a worm wheel 3 driven from a motor, not shown. The table shaft 1 is provided with a worm wheel 4 meshing, as usual, with a worm 5 on the inner end of 50 the governor shaft 6 mounted in the frame 7. Upon the governor or worm shaft 6 is mounted the governor sleeve 8 connected at its inner end to the inner ends of the governor springs 9 provided with weights or balls 55 10; the outer ends of the springs 9 being secured to a collar 11, fixedly secured to the

shaft 6. When the balls or weights 10 are thrown out by centrifugal action the governor sleeve 8 will be moved to the right and with it a slide 12 mounted in a slideway 13 secured to or forming part of the frame 7.

The connection between the slide 12 and sleeve 8 is formed by means of a lateral extension 14 extending at right angles from the slide 12, and provided at its inner end 65 with an aperture 15 through which extends a headed collar 16 secured to the inner end of the governor sleeve. Ball bearings 16' are placed between the adjacent faces of the collar 16 and extension 14. This forms a 70 swiveled connection and permits the governor sleeve to turn freely without rotating the slide and causes the slide to move back and forth with the sleeve under action of its weights and balls. The governor sleeve is 75 thus, in effect, provided with an annular groove 17 receiving the apertured end of the slide.

In moving to the right as the balls or weights fly out the laterally extending end 80 14 of the slide 12 will be brought up against a pad or stop 19 carried by a bell crank lever 20 pivoted at 21 to the frame and having a set-screw 22 at its outer end engaged by the overlying lever 22' pivoted at its inner end 85 to the frame and engaged at its opposite end by an adjusting screw 23. By means of these screws 22, 23 the pad 19 may be set at the exact position it is to occupy just as the pads in prior constructions were set with respect 90 to the rotating brake disks with which they coöperated. The slide 12 is nicely fitted in the slideway 13 so that no rattling is possible, and, since the braking is effected through this slide, it will be termed the 95 braking member or slide. There is no rotary wearing movement of the braking member upon the pad so that it will not wear down and the parts require constant adjustment. Furthermore, the pad and braking 100 member in my construction will bear a constant relation to each other when adjusted, and, even though the pad should get hard or be made of material harder than the felt of which such pads are commonly made, 105 there will be no squeaky noises such as are made by friction. The effective braking action is where the collar 16 pulls upon the lateral extension 14 of the braking member or slide 12, even though a so-called anti-friction or ball bearing be employed at this 110 point, for the greater the tendency of the

weights to fly outwardly, the greater the pull upon the anti-friction member with its consequent clamping or braking action.

I find that motors equipped with my improved mechanism are entirely noiseless and they run better, due to the absence of friction produced by the rotary disk upon a fixed pad. In talking machines absolute noiselessness of the motor and its parts is, of course, of the very highest importance.

Any form of pad or stop and means for adjusting it may be employed in lieu of that shown, as that forms no part of my invention.

15 I claim:

1. The combination with the governor shaft and a centrifugal governor thereon

provided at one end with a loose collar, of a sliding brake member having a laterally extending arm swiveled at its free end to the 20 said loose collar, a guide-way for the slide, and a stop in the path of the said slide to limit its movement.

2. The combination with the governor shaft provided with a centrifugal governor 25 having a flanged collar at one end loose upon the shaft, a sliding braking member provided with a lateral arm having an aperture in which said flanged collar freely turns, a guide-way for the sliding braking member 30 and an adjustable stop in the path of the braking member.

In testimony whereof I affix my signature.
LEVIN H. MULLIKIN.
